D. BOŽIĆ

QUICK ACTION TRIPLE VALVE

Filed Oct. 4, 1923

UNITED STATES PATENT OFFICE.

DOBRIVOJE BOŽIĆ, OF BELGRADE, YUGOSLAVIA.

QUICK-ACTION TRIPLE VALVE.

Application filed October 4, 1923. Serial No. 666,458.

To all whom it may concern:

Be it known that I, DOBRIVOJE BOŽIĆ, a subject of Yugoslavia, residing at Četopečka ul. 6, Belgrade, Yugoslavia, have invented new and useful Improvements in Quick-Action Triple Valves, of which the following is a specification.

The continuous and automatic braking of trains composed of carriages differing from another presents great difficulties which up till now have only been partially surmounted. The present invention has for its object a distributor presenting the following features.

- 16 1. It is applicable to all types of vehicles even when differently loaded and to all compositions of trains.
2. It is entirely automatic.
3. It ensures satisfactory braking of the rolling stock.
- 20 4. It facilitates the operations involved in braking and in making up convoys.

The new distributor illustrated in the accompanying drawing comprises a body 1 equipped with a motor piston 2 and a balancing piston 3 the efforts of which are transmitted to a lever 4 mounted to rock on a fulcrum 5.

The piston 2 is located in the chamber 6 which is in continuous communication with the main train pipe by way of passages 7 and 8. The piston-rod 9 is hollow and issues from the chamber 6 through a tight fitting packing. Centrally of the motor piston 2 is the interrupter piston 10 the piston-rod 11 of which penetrates the piston-rod 9 and engages the lever 4. The cavity 12 between the pistons 10 and 2 communicates with the atmosphere by way of the groove 13.

Above the pistons 2 and 10 is a diaphragm 14 which separates the chamber 6 and the cavity 12 hermetically from the compartment 15. The spring 16 urges the piston 2 against the diaphragm 14.

The compartment 15 is separated by the diaphragm 17 from the space 18 which is in continuous communication with the main train pipe by way of the passages 19 and 20. The diaphragm 17 has a port 21 which is normally closed by the needle valve 22 the stem 23 of which is led through a tightly fitting packing in the body 1. The spring 25 bearing against the shoulder 26 maintains

the stem 23 in a fixed position. A handle 24 permits manipulation of the needle valve.

The balancing piston 3 separates the chamber 28 from the atmosphere; its piston-rod 27 engages the lever 4.

The piston 3 has a central port adapted to be closed by an exhaust valve 30 depending on the position of the piston. This port and the passage 29 establish communication between the chamber 28 and the atmosphere when the valve 30 is open.

The exhaust valve 30 is integral with the inlet valve 31 controlling communication between the chambers 32 and 28, the chamber 32 being in continuous connection with the auxiliary reservoir. The chamber 32 is connected to the chamber 6 and, consequently, to the main train pipe, by way of the passage 34 controlled by the ball valve 33.

Between the chamber 28 and the chamber 36 (which last mentioned chamber is in continuous communication with the brake cylinder) is interposed a valve 35 integral with the piston 39, the said piston 39 being formed with a port 40. The spring 41 maintains the valve 35 normally in open position.

The space below the piston 39 is connected to the passage 42 controlled by the valve 43 which, when in closed position, prevents air from the brake cylinder from escaping to the exterior. The stem 44 of the valve 43 may be lifted by the lever 45, which is urged downwards by the spring 46 or by the counter weight 47. This lever, which may work on either of the knife edges 52, 53, is articulated at 480 to the link 48 which carries the brake-shoe 49 and the connection 51 by the operation of which the brake shoe 49 may be pressed against the wheel 50.

The stem 54 bears on the axle box 55 and supports the arm 56 of the lever 57 which rocks on the stationary knife-edge fulcrum 58.

The arm 59 of the lever 57 is lighter than the arm 56 and supports through the intermediary of the adjusting screw 60 the arm 61 of the ball-crank lever 62 the other arm 63 of which operates the slide 64 carrying the fulcrum 5 of the lever 4.

The displacement of the slide 64 is limited at the right hand side by the screw 65. On high speed vehicles the slide 64 is connected to the piston 66 by the rod 67. On the left hand side of the piston operates the atmos-

pheric pressure and the stress of the spring 68 while the space 69 to the right of the piston is connected by the passage 70 with the main train pipe or with the auxiliary reservoir or with the compartment 15. A spring 68 urges the piston 66 towards the right.

From the passage 8 leads a passage 71 having a branch 72 which leads to the chamber 73 above the piston 74. The stem 76 of the piston 74 passes through the end wall of the chamber 75 and its lower end 77 functions as a valve for cutting off communication between the passage 71 and the passage 15 78 leading to the atmosphere.

The piston 74 is urged downwards by the spring 79. To the stem 76 is fitted the valve 80 which closes the passage from the chamber 73 to the chamber 75. The valve 80 is integral with the piston 81 located in the passage 82 and has a cap 85 which enters the space 86, having only slight lateral play therein. The passage 82 is connected to the passage 71 by the port 83.

The operation of the distributor is as follows:—Compressed air from the main pipe enters by the passages 8 and 7 into the chamber 6; thence it flows through the passage 34 after lifting the ball valve 33 to the chamber 32 and thence to the auxiliary reservoir. Further, compressed air passes by way of the passage 20 and groove 19 into the space 18 and, unseating the diaphragm 17, fills the compartment 15. The distributor is then 35 ready for operation.

If the pressure in the main pipe, and consequently, in the chamber 18 is lowered, the difference of pressure which is then set up between the compartment 15 and the chamber 6 flexes the diaphragm so that the pistons 2 and 10 are caused to descend, and, acting through the stem 11 on the lever 4, cause the right hand end of the lever to fall and the left hand end to rise. The left hand end of the lever 4 lifts the balancing piston which acts on the valve 30 to cut off communication between the brake cylinder and the atmosphere. The valve 31 is now in raised position and compressed air from the auxiliary reservoir enters the chamber 28 and passing the valve 35 flows through the passage 36 to the brake cylinder.

At the moment when the pressure in the brake cylinder and in the chamber 28 produces on the piston 3 an effort exceeding that transmitted by the pistons 2 and 10, the lever 4 rocks and occupies a position of equilibrium in which the valves 30 and 31 are both closed.

Every further reduction in pressure in the train pipe produces like effects until the effort on the piston 3 balances that exercised by the pressure in the chamber 15 on the interrupter piston 10 the space below which 65 is in communication with the atmosphere.

At this moment the piston 10 is urged upwardly until the valve 31 engages its seat and cuts off communication between the auxiliary reservoir and the brake cylinder even if the reduction of pressure in the train 70 pipe is accentuated.

The effect on the pistons 2 and 10 depends only on the variations of pressure in the train pipe, whereas that transmitted by the lever 4 to the balancing piston 3 depends 75 on the position of the fulcrum of the lever 4. The pressure in the brake cylinder is thus a function of the position of the fulcrum 5 and will be greater the further to the left is brought the fulcrum 5. The extreme right hand position of the fulcrum corresponds to the empty condition of the wagon; the extreme left hand position corresponds to the fully loaded condition of the wagon.

The displacement of the slide 64 is controlled by deformations of the suspension springs 550. When the wagon is loaded, the springs 550 flatten and the stem 54 lifts the arm 56 of the lever, lowering the arm 59 so that by the action of gravity on the ball crank lever arm 61 the arm 63 of the ball crank lever shifts the slide 64 and, consequently, also the fulcrum 5 to the left.

When the load of the wagon is diminished 95 the arm 56 of the lever 57 which is of preponderating weight causes the slide to return to the right. These movements are only possible when the brake is released because as soon as the braking operation commences the pistons 2, 10 and 3 press the slide 100 64 powerfully against the body 1 so that the slide is rendered immovable. There are thus avoided variations of the braking action brought about by oscillations of the 105 suspension springs due to irregularities of the track. The screw 65 affords a means of limiting the displacement of the slide 64 towards the right and of controlling the 110 braking effort according to the relation between the maximum load and the tare. The screw 60 serves for adjusting the fitting when erected and for making corrections due to deformation of the suspension springs or of other parts.

If now the pressure in the main pipe and, consequently, in the chamber 6 is increased, the effort on the pistons 2 and 10 will diminish and permit the balancing piston to descend and open the valve 30. The air in the cylinder of the brake escapes through the passage 29 until a state of equilibrium is again arrived at. Other increases of pressure will produce identical effects until the moment when the pressure again becoming 120 equal to the initial pressure the parts resume the position shown in the drawing. The brake cylinder is then completely empty.

The release of the brakes may be effected 125

otherwise. On retraction of the handle 24 the valve 22 unmasks the port in the diaphragm 17 and the pressure in the compartment 15 rapidly becomes equal to that in the 5 train pipe. There being now no effort on the pistons 2 and 10 the brake is released.

If the vehicle becomes a component of an express train having brakes arranged to operate at high pressure, this high pressure 10 displaces the piston 66 as the spring 68 is able to balance the working pressure in ordinary trains. The slide 64 now moves to the left, as the result of which the maximum braking effort is obtained. When the speed 15 of the vehicle diminishes, the wheels would be locked if this effort were maintained. To avoid this, the brake shoe 49 transmits tangential effort to the lever 45. There being two fulcra 52 and 53 for the lever 45, 20 the lever 45 shifts as soon as the effort due to the presence of the spring 46 or of the counter weight 47 is overcome, that is at the moment when the coefficient of friction of the shoe on the wheel becomes such that the 25 locking of the wheels is imminent. At this moment the lever 45 lifts the valve 43 permitting an escape from the passage 42 and, consequently, from the brake cylinder. This escape of air results in a difference of pressure 30 on the two sides of the piston 39 which will then move downwards, the valve 35 becoming seated and cutting off communication between the auxiliary reservoir and the brake cylinder. The cylinder will now be 35 emptied progressively, the air escaping past the valve 43, diminishing the braking effort, until the moment when the tangential effort of the shoe 49 is no longer able to overcome the spring 46 or the counter weight.

40 If the vehicle is coupled to a normal train the piston 66 reassumes its initial position under the action of the spring 68 and the operation is as above described.

The operation of the accelerator will be 45 described below. Compressed air from the pipe enters by way of the passages 8, 71 and 72 into the chamber 73 and, in consequence of the clearances permitted, enters the chamber 75 where the working pressure is established. With gradual slow fall of pressure in the train pipe the air in the chamber 75 gradually escapes and pressure equilibrium 50 between the chambers 73 and 75 is established as before due to the clearances aforesaid. If the fall of pressure is abrupt the air escapes from the chamber 75 by lifting the piston 74 and, consequently, opening the valve 77, permitting air from the main pipe to escape to the outside by way of the passage 78. At the moment when the piston 74 abuts against the bottom of the chamber 73, the valve 80 leaves its seat, due to inertia, and equilibrium of pressure is established 55 between the chambers 73 and 75 by the passage 84, which brings about the descent of

the piston 74 under the influence of the spring 79. The valve 80 cannot resume its closing position before the piston 74 has fallen completely due to the excess pressure prevailing at this moment in the chamber 75 70 and in the space 86 under the cap 85.

As soon as the valve 77 is seated, the drop in pressure in the train pipe ceases and the accelerator is ready for operation anew. The passage 72 may be dispensed with and 75 the valve 85 and its stem may then be bored to present a passage which affords communication between the chamber 73 and the space 82 and passage 71.

Having now fully described and ascertained my said invention, and the manner in which it is to be performed, I declare that what I claim is:—

A distributor for brakes operated by fluid pressure characterized by the provision of 85 one or more of the following features:—

1. In a distributor for brakes, an interrupter piston, a compartment in which said piston works, a diaphragm dividing said compartment, one side of said diaphragm 90 being exposed to a determinable pressure and the other in part to the pressure in the train pipe and in part to atmospheric pressure, a balancing piston, a lever adapted to be engaged by said pistons, a movable fulcrum for said lever, and means controlled by the load of the vehicle to be braked for varying the position of said fulcrum to effect variations in the relation of the efforts of 95 said pistons, for the purpose stated.

2. The combination in a distributor for brakes operated by fluid pressure, of a lever, a movable fulcrum on which said lever is mounted, a motor piston adapted to engage said lever, a chamber within which said piston works, a diaphragm dividing said chamber, a balancing piston also adapted to engage said lever, a cylinder within which said piston works, an auxiliary 100 reservoir, a brake cylinder, means for supplying pressure to said auxiliary reservoir, means for creating a difference in pressure in the two divisions of the said chamber thereby to operate the motor piston and thereby to operate the balancing piston through said lever, means operated by the balancing piston to transfer the air pressure from the auxiliary reservoir to the brake cylinder, and means operated by the load of the vehicle to be braked for adjusting the position of the fulcrum of the lever according to 105 said load.

3. In a distributor for brakes operated by fluid pressure, an interrupter piston and a balancing piston, a lever adapted to be engaged by said pistons, a shaftable fulcrum on which said lever is mounted, means operated by the load of the vehicle to be braked for automatically varying the position of 115 said fulcrum to effect variations in the re- 120

lation of the efforts of the said pistons upon said lever, and consequently on the pressure in the brake cylinder for a given fall of pressure in the train pipe, and means for bringing about a release of the brakes at any desired time.

4. In a distributor for brakes operated by fluid pressure, an interrupter piston and a balancing piston, a lever adapted to be engaged by said pistons, a shiftable fulcrum on which said lever is mounted, means operated by the load of the vehicle to be braked for automatically varying the position of said fulcrum to effect variations in the relation of the efforts of the said pistons upon said lever and consequently on the pressure in the brake cylinder for a given fall of pressure in the train pipe, and means for preventing the locking of the wheels of the vehicle by the braking effort.
5. In a distributor for brakes operated by fluid pressure, an interrupter piston and a balancing piston, a lever adapted to be engaged by said pistons, a shiftable fulcrum on which said lever is mounted, means operated by the load of the vehicle to be
- 10
15
20
25

braked for automatically varying the position of said fulcrum to effect variations in the relation of the efforts of the said pistons upon said lever and consequently on the pressure in the brake cylinder for a given fall of pressure in the train pipe, and means for causing the braking effort to be varied automatically when the working pressure is altered from its normal value to that corresponding to high-pressure braking.

6. In a distributor for brakes operated by fluid pressure an interrupter piston and a balancing piston, a lever adapted to be engaged by said pistons, a shiftable fulcrum on which said lever is mounted, means operated by the load of the vehicle to be braked for automatically varying the position of said fulcrum to effect variations in the relation of the efforts of said pistons upon said lever, and consequently on the pressure in the brake cylinder for a given fall of pressure in the train pipe, and means for preventing irregularities in the braking action due to irregularities in the track.

DOBRIVOJE BOŽIĆ.

Certificate of Correction.

It is hereby certified that in Letters Patent No. 1,571,506, granted February 2, 1926, upon the application of Dobrivoje Božić, of Belgrade, Yugoslavia, for an improvement in "Quick-Action Triple Valves," an error appears in the printed specification requiring correction as follows: Page 3, line 84, beginning with "A distributor" strike out all to and including the word "features" in line 86; and that the said Letters Patent should be read with this correction therein that the same may conform to the record of the case in the Patent Office.

Signed and sealed this 9th day of March, A. D. 1926.
